(57) **CLAIM**

The ornamental design for a flexible alarm clock, as shown and described.

DESCRIPTION

FIG. 1 is a perspective view of the front and left side of a flexible alarm clock showing my new design;
FIG. 2 is rear view of the design of FIG. 1; and,
FIG. 3 is a perspective view of the design of FIG. 1, with portions of the design having been twisted into an alternative configuration.

1 Claim, 2 Drawing Sheets

FIG. 1

FIG. 2

FIG. 3
